Charles E. Hensley
ATTORNEY

UNITED STATES PATENT OFFICE.

BENJAMIN K. TAKENAKA, OF NEW YORK, N. Y.

REMOVABLE BRIDGE FOR ARTIFICIAL TEETH.

Application filed August 10, 1925. Serial No. 49,355.

There is in use at the present time what is known as removable or detachable bridges for artificial teeth. By means of such devices it is possible to provide one or more 5 artificial teeth mounted in a plate or saddle, and having at each side a connecting member which interlocks with a socket member mounted in an inlay in the natural teeth, at either side of the artificial tooth or 10 teeth. The object of the removable bridge is to permit the artificial teeth to be removed for cleaning and to permit them to be quickly restored to position. It has been necessary to provide some means of locking 15 the artificial bridge in position so that the artificial teeth would not be dislodged accidentally. Usually this locking means has consisted of a locking member consisting of a split key which could be forced 20 apart more or less from time to time in order to take up for wear between the locking members. One objection to this has been that the patient had to return to the dentist each time an adjustment was to be 25 made, and in addition, the adjustment was not reliable and permanent.

The object of my present invention is to provide a simple and effective spring device for locking the removable bridge in 30 place and which will permit the bridge to be removed from time to time, as often as desired, and to provide a locking device which may be adjusted by simply turning a screw or screws, and this adjustment may 35 be made by the patient. The present device is simple in construction and operation and permits the artificial teeth to be removed as often as desired.

In the drawing forming part of this application,

Figure 1 is a perspective view representing a portion of the human gum with two natural teeth provided with inlays and with a single artificial tooth lying between the 45 same and connected by means of my invention.

Figure 2 is a sectional view of the locking device taken on the line 2—2 of Figure 3,

Figure 3 is a plan view of the locking members, and

Figure 4 shows a perspective of the various parts of the locking device.

In the drawing I have shown a portion 1 55 of the human gum and in connection therewith I have shown two teeth 2 and 3 sepa-

rated from each other by a space previously occupied by an intermediate tooth which has been extracted and which is to be 60 supplanted by an artificial tooth. It will be understood that the space to be filled between the natural teeth may require one or more artificial teeth, according to the number of extracted teeth, but for the purpose of teaching the use of my invention it is 65 sufficient to illustrate the application of a single tooth. Where there are several artificial teeth it will be understood that they are all mounted in a common saddle, and the locking device forming the subject of my 70 invention will be provided at opposite ends of the saddle in the same manner, regardless of whether the saddle contains one or more artificial teeth.

In Figure 1 I have shown a saddle 4 of usual form, and partially surrounding and holding the artificial tooth 5. The saddle also includes a plate portion 6 which rests against the gum so that part of the pressure comes against the gum. This saddle 80 extends upwardly and partly over the crown of the tooth at 7 and another portion extends around the base of the tooth at 8. The teeth 2, 3 at opposite sides of the artificial tooth are each provided with an inlay 9 95 in well known manner, and each inlay includes a socket member forming part of the present locking device. As shown in the drawing, each socket member consists of a member 10 as shown in the several figures. 90 This member has a wall 11 extending vertically in the inlay and at the side edges the socket curves at 12 and is formed into an opposite wall 13 which has a central opening or slot 14. The upper end of the socket is open, whereas the bottom is usually closed by a bottom wall 15. The socket is permanently fixed in each inlay and the pair of sockets face each other as shown in Figure 1. Preferably there is a U-shaped member 16 which is fitted against the wall 13 of the socket for the purpose of stiffening 95 and strengthening the construction.

At each side of the saddle there is a locking device and as both of these are the 105 same, except that they face in opposite directions, a description of one will answer for both. There is a post 17 which is inserted into the saddle, to wit, into the member 7 of the saddle, and usually this member is 110 welded to the latter. At the free end of this supporting member there is extending at

right angles to it, a locking member consisting of the plate 18, which has the rounded ends 19, the plate extending at right angles to the supporting member 17 forming a ⁵ T shaped construction. Intermediate the curved ends 19 there is a curved outer surface 20 which permits of the adjustment of the spring as will be set forth.

There is a spring member 21 shown in Figure 4 having the curved portions 22 which fit around the curved ends 19 of the member 18 and the front plate of this spring member is slightly curved or arched at 23 to partially correspond with the curvature ¹⁵ of the surface 20; and this wall 23 is provided with an aperture 24 to receive the shank of the screw 25; and around this aperture the metal is countersunk at 26 to receive the head 27 of the screw. The members 17 and 19 are provided with a threaded aperture 28 to receive the screw.

The spring is assembled by being placed endwise over the member 18 and pressed downwardly until these parts coincide at the ²⁵ top and bottom edges; and the screw 25 is inserted through the spring and into the aperture 28 and is partially screwed until the plate 23 of the spring is pressed slightly into the curved recess 20 of the member 18. ³⁰ When the device is first put into use the screw will be only partially turned down and this action tends to draw the curved portions 22 of the spring around the curved edges 19. This action tends to force the ³⁵ spring outwardly at the points 29; and the edges 30 of the spring, in drawing around the curved members 19 have a tendency to force outwardly against the socket. The position of the spring will be adjusted so that ⁴⁰ the locking member with its spring will slide endwise into the socket 10 with sufficient friction to hold the artificial tooth in place. This adjustment will be made on the locking device on each side of the artificial tooth so that both locking devices slide into their respective sockets and hold the artificial tooth in place. After repeated removals and replacing of the artificial tooth there will be ⁴⁵ a slight relaxation of the grip in the sockets by the locking member, due to wear of the parts, and when there is insufficient friction to hold the artificial tooth in place it is only necessary to remove the same and to screw the screws 25 further into the aperture ⁵⁰ 28 at each side of the saddle whereupon the curved portion 23 of the spring will be forced nearer the curved surface 20. This will increase the outward tension of the

spring in the manner above described, so that the spring will again tightly engage in ⁶⁰ the socket. This adjustment may be repeated from time to time as the parts become worn so that there will always be a proper degree of friction to retain the artificial tooth in place. It will be obvious that this ⁶⁵ adjustment is very simple and it may be made by the patient without having to revisit the dentist.

Having described my invention, what I claim is:

1. In a removable bridge for artificial teeth the combination of a saddle having one or more artificial teeth mounted therein, and means for detachably securing the saddle to an inlay in an adjacent tooth comprising a ⁷⁵ socket member having a vertically extending slot in one side and a vertically extending pocket having rounded ends and cooperating locking members substantially T-shaped, the shank of which is adapted to move in the ⁸⁰ vertical slot of said socket member, the head of said T shaped member being adapted to slide in the socket member and having a recessed surface to provide a space between said recessed surface and the adjacent surface of the socket, a spring curved around the ends of said T shaped head and lying between the same and said socket, and a screw for bending the said spring in said space for adjusting the frictional engagement between said locking members. ⁹⁰

2. In a removable bridge for artificial teeth the combination of a saddle having one or more artificial teeth mounted therein, and means for detachably securing the saddle to an inlay in an adjacent tooth comprising a ⁹⁵ socket member having a vertical slot and a vertically disposed socket provided with rounded ends, a cooperating locking member substantially T shaped, the stem of which is adapted to slide in said vertical slot of said socket member, the head of said T shaped member being adapted to slide vertically in said socket and having rounded ends, and an intermediate curved surface, a ¹⁰⁰ spring curved around said ends of said head, and lying between the head and the socket member, and a screw threaded into said T shaped locking member and adapted to press said spring towards said curved surface for ¹⁰⁵ the purpose of increasing the frictional contact between said members. ¹¹⁰

Signed at the city, county and State of New York, this 2nd day of June, 1925.

BENJAMIN K. TAKENAKA.
